United States Patent Office

Des. 178,935
Patented Oct. 9, 1956

178,935

GAME DICE AGITATOR OR SIMILAR ARTICLE

George D. Smith, Brooklyn, N. Y.

Application March 24, 1955, Serial No. 35,190

Term of patent 14 years

(Cl. D34—5)

Fig. 1

Fig. 2

Fig. 3

Fig. 1 is a perspective view of a game dice agitator or similar article, showing my new design;

Fig. 2 is a front elevational view thereof, the dice being shown in a different position; and

Fig. 3 is a side elevational view thereof.

I claim:

The ornamental design for a game dice agitator or similar article, as shown.
